The ornamental design for a display screen with graphical user interface, as shown and described.

DESCRIPTION

FIG. 1 is the first image in a sequence of a display screen with graphical user interface showing our new design according to a first embodiment;
 FIG. 2 is the second image thereof;
 FIG. 3 is the third image thereof;
 FIG. 4 is the fourth image thereof;
 FIG. 5 is the fifth image thereof;
 FIG. 6 is the sixth image thereof;
 FIG. 7 is the seventh image thereof; and,
 FIG. 8 is the eight image thereof.

The features shown in broken lines in the drawings depict environmental subject matter only and form no part of the claimed design. The dash-dotted lines denote the boundaries of the claimed design and form no part thereof. The subject matter in this patent includes a process or period in which an image changes into another image. The process or period forms no part of the claimed design.
